AUTOGRAPHIC REGISTER

Fritz G. Diesbach, Hamilton, Ohio, assignor to
 Krauth & Benninghofen, Hamilton, Ohio, a
 firm

Application November 20, 1934, Serial No. 753,931

3 Claims. (Cl. 282—21)

This invention relates to improvements in autographic registers or manifolding machines by means of which a continuous strip or strips of paper or continuous form stationery is fed from a supply compartment in the machine onto and across a writing table or platen and delivered therefrom in predetermined lengths, whereupon sections of the strips may be severed or torn from the strips.

10 The strips are supplied in reel or packet form, the packet form being herein disclosed. In the packet form a plural number of strips are disposed in superposed arrangement and in zigzag folds, the line of fold being disposed in the 15 spacing between forms printed upon the strips. The strips also contain filing holes likewise located in the spaces between the forms. These holes are utilized in the passage of the superposed strips through the machine for governing the withdrawal of the strips causing the strips to issue in measured lengths, each length representing the full length of a printed form. Moreover, the holes align and register the 20 printed forms of the superposed strips as disposed on a writing table for entry and manifolding purposes, holding the same in properly registered position against disarrangement while entries are being made.

In the type of mechanism to which the present 30 invention is directed as an improvement, these apertures or filing holes are utilized for administering a mechanical short feed advance of the strips to project the forward ends thereof sufficiently from the delivery end of the machine for 35 convenient grasp by the operator, whereby he can manually continue the withdrawal until withdrawal is again arrested by means of the pins or detents, as a part of the control mechanism, automatically engaging the next successive set of 40 apertures when they are brought into registry with the pins.

It is the object of the present invention to provide an improved mechanical short feed advance means for the purposes above set forth; in other 45 words, an improved device operating in relation to the apertures in the strip for initiating the advance of the strip projecting the end thereof sufficiently beyond the delivery end of the machine, whereby the operator can grasp the projected ends of the strips and manually continue 50 strip withdrawal. It is a further object to provide that this starting mechanism will be automatically effective for controlling and limiting the amount of manual withdrawal of the strip 55 accurately and positively stopping the strip in

relation to the severing edge, so that severance takes place accurately between the forms.

Other objects and further advantages will be more fully apparent from a description of the accompanying drawings, in which:

Figure 1 is a fragmentary plan view of an autographic register, showing the delivery end thereof.

Figure 2 is a sectional view taken on line 2—2, Fig. 1, showing the pins in the apertures of the 10 strips prior to starting feed.

Figure 3 is a sectional view taken on line 3—3, Fig. 2.

Figure 4 is a sectional view taken on line 4—4, Fig. 3, showing the forward position of the pin 15 carrier or mechanical feed starting mechanism in dot and dash lines.

Figure 5 is a sectional view taken on line 5—5, Fig. 3, showing the pin carrier or feed starting device in forward position and as the pins are 20 being withdrawn from the apertures in the strips.

Figure 6 is a fragmentary sectional view taken from Fig. 5, but showing the pins returned and in position for interception of strip feed and illustrating the operation of manually pulling 25 the strips from the machine.

Figure 7 is a fragmentary sectional view taken similar to Fig. 4, but showing a modified form of pin carrier or feed starting mechanism.

Figure 8 is a sectional view taken on line 8—8, 30 Fig. 7, showing the pins in position prior to feed starting movement.

Figure 9 is a sectional view taken on line 9—9, Fig. 8.

Figure 10 is a sectional view taken on line 35 10—10, Fig. 9, showing the starting mechanism in forward position and as the pins are being withdrawn from the apertures.

Figure 11 is a fragmentary sectional view taken similar to Fig. 7, but showing the forward feed 40 position of the feed starting mechanism.

Figure 12 is a fragmentary sectional view taken from Fig. 10, showing the manual operation of withdrawing the strips from the machine with the pins returned and in position to engage the 45 next set of apertures for interception of strip feed.

In the embodiments of the invention disclosed herein a depressible pin carrying unit is pivoted at its lower end, permitting an oscillating movement of the upwardly extending pins somewhat longitudinally of the platen or of the strips. The forward mechanical feed or starting movement of the unit is accomplished by means of a lever, either fixed to or acting upon the unit for causing 50 55

a forward swing of the pins. This forward swinging movement is against spring pressure. As the pins move forwardly they are forced downwardly by spring means tending to extract them from the apertures in the strips. After a forward movement sufficient for projecting the ends of the strip beyond the machine, whereby they can be readily grasped for hand extraction, the pins are completely withdrawn and the return spring on the unit is effective for returning the pins to their initial position except that they are still depressed due to the fact that upward movement is obstructed by the strips.

As soon as the strips have been extracted manually an appropriate distance the next apertures in the paper register with the pins and the pins move upwardly into the apertures blocking further longitudinal movement of the strips and placing the pins in position for the next starting operation.

The movement of the pins is approximately rectilinear. This rectilinear motion takes place about control lugs. The forward or starting feed movement of the pins is across the top of the lugs. When past the lugs the spring action causes downward movement in front of the lugs, clearing the same and permitting the return spring to swing the unit back to its normal position of alignment passing under the lugs. Then follows a delay while the paper is being withdrawn, but as soon as the succeeding apertures align with the pins the fourth side of the rectilinear motion is completed by upward movement of the pins past the lugs at the rear thereof to the starting position for feed movement across the top of the lugs as above set forth.

The forces acting on the swinging pin carrier in its movement around the control lug are as follows: First of all, a manual force is applied to the unit swinging the pins forward and imparting starting feed to the strips for projecting them as heretofore described; spring means forcing the pins downwardly out of the apertures in the strips; a return spring swinging the unit back to starting position across the underside of the lowermost strip; and springs constantly urging the unit upwardly for immediate entrance of the pins into the apertures as aligned therewith.

The general type of mechanism to which the present construction is directed as an improvement, in other words mechanism for starting the feeding advance of the superposed strips or web to project the forward end thereof beyond the delivery end of the machine, is shown and described in United States Letters Patent No. 1,333,082, issued to A. Krauth, March 9, 1920, as well as in United States Letters Patent No. 1,982,606, issued to Fritz G. Diesbach, November 27, 1934.

In the mentioned patents a swinging lever member is employed carrying depressible pins engageable respectively with apertures in the strips when these apertures are disposed in registry therewith in the movement of the strips over the writing table. Also, the mentioned disclosures show means for controlling the strip withdrawal in measured lengths governed or regulated by apertures spaced longitudinally of the strips.

Referring to Figures 1 to 6, inclusive, of the drawings, the frame or casing of the machine is generally indicated at 15 and includes a bottom 16, side walls 17 and end walls 18. In view of the absence of improvement or difference at the rear end of the machine over the mentioned application and patent, only the forward end of the

machine is disclosed and detailed in the present application; in other words, only so much of the machine as deals with the withdrawal control as opposed to the feeding of the strips from a pack or roll onto the platen or writing table.

The casing includes a compartment 19 for a supply pack of paper or a continuous form of stationery 20 composed of a plurality of superimposed strips in zigzag fold or packed form. This compartment is defined by subdividing the interior of the casing by means of a partition or wall 21 rigidly secured to the bottom of the casing (see Figure 2).

The strips are fed as a unit from the supply pack to the rear end of the machine extending and engaging over a writing table or platen 22 and supported on the side walls of the casing. This writing table or platen may be removable or hinged for access to the supply compartment. Since the removable nature of this platen is well understood in the art, no disclosure is made of the details thereof in this instance.

The margin frame 23 is hingedly or removably secured to the casing including flanges 24 overhanging the side walls and flanges 25 overlying the writing table marginally thereof. The hinged or removable connection of the margin frame to the casing is not disclosed herein.

The mechanical feed starting means heretofore referred to is in the nature of a pivoted plate unit, generally shown at 26, and located within the forward compartment of the machine. This unit is pivotally supported in the side walls of the casing. The plate assembly includes a main vertical carrier or leaf member 27 directly pivotaly mounted on a cross rod 28 secured to and between the side walls of the casing. Cross pins 28^a fixed in the rod maintain the carrier against lateral displacement on the rod. A vertically movable pin carrying plate 29 lies flat against the main carrier plate 27 and is slidably connected thereto by T-lugs 30 stamped or punched from the material of the main plate or leaf member and engaged respectively through T-slots 31 in the vertical slide plate. A screw 32^a limits downward movement of the slide plate 29 so that it cannot become dismounted by registration of the lugs and slots.

There are three of these T-lug and slot connections. Each of two of the lugs has a spring 32 connected thereto and to an ear or lip 33 punched outwardly from the slide plate. These springs normally yieldingly hold the slide plate in an elevated position limited by the engagement of the lugs 30 with the base of the T-slots 31. The upper edge of the vertically mounted slide plate has a pair of laterally extended ears 34, each ear carrying an upwardly extended pin 35, which pins it will be apparent are yieldably depressible by virtue of their mounting on the spring retained slide plate.

The pins are spaced apart a distance corresponding to the crosswise spacing of the apertures in the strips, whereby they engage therethrough when a set of apertures are brought into registry therewith. As stated, the pin carrying slide plate 29 being normally urged upwardly by the springs causes the pins to maintain contact with the underside of the strips or the lowermost strip where they are in position to snap through the apertures in the strips at once when brought into registry therewith, and accordingly arrest or withhold strip advance, automatically controlling or regulating the strip withdrawal to definite measured lengths corresponding to the distance 75

of the aperture spacing longitudinally of the strips.

For reasons of clearance, hereinafter more apparent, the pins engage through elongated slots 36 in the forward end of the writing table or platen and the forward margin flange 25 therefore projecting above the writing table when engaged through the apertures of the strips. The carrier plate and pin carrying plate as an assembled unit are held to a vertical position by means of a spring 37 having its respective ends attached to a lug 38 secured on the carrier plate and to an ear 39 punched outwardly from the side wall of the casing. The carrier at vertical position engages a stop on a cross bar 40 for limiting the rearward swing of the carrier and slide plate as a unit as urged by the return spring to vertical alignment.

The feed advance or mechanical starting of the strips for projecting the forward end of the strips beyond the delivery end of the casing in position for a hand hold on the strips for continued withdrawal is accomplished by rocking or swinging the pin carrier and slide plate assembly forwardly. This is done by means of an arm 41 fixed to the pivoted carrier plate and projected laterally from the machine casing through a slot 42 in the side wall thereof, the outer end 41^a of the arm being shaped to fit the finger and projected a sufficient distance for easy access. The lug 38 to which the spring 37 is secured is an integral part of this arm.

As the unit is swung forwardly on its pivot by manual pressure on the operating arm extended therefrom, the depressible slide plate carrying the pins is urged downwardly against the pressure of the springs 32. This downward thrust is caused by the engagement of the upper edge 43 of the slide plate with a spring plate cam strip 44 secured medially to the cross bar and curved downwardly forwardly.

As shown in Figures 3 and 5, lugs 45 are extended inwardly from the cross bar at each side of the slide plate. These lugs are adapted to register and cooperate with slots 46 in the respective side edges of the slide plate. The ears 34 on the slide plate which carry the pins ride across and over these lugs 45 on the cross bar as the plate is urged in a downward direction by contact with the underside of the cam strip. As soon as the ears 34 are past the lugs 45 of the cross bar (see Figure 5), downward movement of the slide plate takes place for complete extraction of the pins from the filing holes in the strips as shown in Figure 5.

The pins moving downwardly a sufficient distance by virtue of the cam contact clear the lugs which causes complete movement of the pins from the apertures, thereby clearing the strips and permitting manual withdrawal of an appropriate strip length.

The moment the pins are clear, that is, have been depressed below the strips, the return spring 37 will pull the pin carrying unit rearwardly with the pins in contact with the underside of the lowermost strip (see Figure 6), in which position the pins are ready to move upwardly the moment this contact is no longer available as when the next succeeding apertures move over the pins. At this juncture the pins immediately move upwardly and register with the apertures automatically stopping further manual withdrawal of the strip (see Figure 2). At this time, after a complete rectilinear movement of the pins around the lugs 45, a full form length has been withdrawn and

the operator can tear the projected portions of the strip along the tear-off edge 45 established by the forward edge of the margin plate.

It will be noted that the cross bar is cut out at 46 intermediate its length to provide clearance 5 for the pin carrying ears of the slide plate and includes a downwardly turned flange 47 forming the vertical alignment stop for the pin carrying unit heretofore referred to.

In the modified form of the invention shown in Figures 7 to 12 inclusive, the same principle of operation is involved. That is to say, the pins move in a rectilinear path as acted upon by various mechanical means employed and herein-after described.

In this form a supporting wall structure 50 is incorporated in the forward compartment of the machine. This wall structure consists of a vertically disposed plate 51 secured to the floor of the casing and having its upper end attached to a cross rail 52 attached to the respective side walls of the casing. The pin carrying unit or mechanical feed starting mechanism, as in the preceding form, consists of two plate elements, one of which is the swinging carrier plate 27 having its lower edge pivotally mounted on a pivot rod 53, and the other of which is the vertically movable pin carrying plate 29 slidably mounted flat against the first plate by the same means employed in the first form; that is, the T-shaped lugs 39 and slots 31. Also, the means for constantly urging this plate upwardly is in the form of the springs 32 arranged as in the preceding form.

The pivot rod 53 is journalled within the casing in flanges 54 struck up from the base flange 55 of the support wall 50 heretofore described, the pivot plate being confined against lateral displacement between these flanges.

In this form a spring 56 having one end anchored on a screw 57 on the support wall and the other end anchored on a tang 58 struck out from the metal of the vertically slid able pin carrying plate, is under tension for constantly urging the pin carrying plate downwardly. This tang 58 is projected through a vertical clearance slot 59 45 in the pivot plate.

A coil spring 60 under tension is anchored on and between the support wall and the pivot plate respectively, constantly pulling the pivot plate rearwardly to normal, substantially vertical position, this being the spring for returning pins to normal position by passage under the lowermost side of the strips. The screw 61 anchoring this plate to the swinging pivoted plate also functions as a stop to limit vertical downward movement of the slide plate.

An operating lever 62 pivoted on the support wall has one end 63 projected externally of the casing through a slot in the side wall thereof, and the other end 64 projected between the support wall and the swinging plate. This lever is mounted on a pivot lug 65 and a coil spring 66 is employed about the pivot for urging the lever constantly to normal position away from the swinging plate assembly. The inner end of this lever is disposed in a slot 67 in the circular hub of a locking finger 68 pivotally mounted on a lug 69 of the support wall between the support wall and the swinging plate. The finger 68 projects through vertical slots 70, 70^a, in the vertically movable plate and swinging plate respectively, and includes a notch 71 cooperating with the edge of the vertically movable plate at the upper end of the slot therein. The edge 72 of the finger 75

is inclined from a pointed end to this notch for a cam action hereinafter more apparent.

A control lug 45, heretofore described in the preceding form, is in this instance formed by 5 striking out a portion of the support wall, projecting this portion forwardly and including a horizontal laterally extended flange which is the lug 45 proper. This portion extends through the clearance slot 59 in the vertically movable 10 pin carrying plate 29. A lug portion or ear 73 of the material of this plate 29 projects over the lug 45 as shown in Figures 9 and 10.

In the operation of this modified form, the following movements take place. When the operator 15 swings the operating lever 62 he rotates the finger out of contact or locking engagement with the upper edge of the slot in the swinging plate, permitting the swinging plate to be swung forwardly as the end of the lever engages the same. 20 This movement carries the pins forwardly and projects the strips a short distance from the machine, as has been described. Forward movement of the plate carries the extended ear or lug 73 of the vertically movable plate over the control lug 45, the control lug functioning to prevent downward movement of the pin carrying plate under the action of the spring until the ear portion clears the forward end of the lug.

At this time (see Figure 10) the spring 56 is 30 effective for depressing the plate and extracting the pins from the apertures, a direct downward movement ensuing in front of the control lug.

Assuming a release of the operating lever as 35 soon as this depressive movement of the pins has occurred, the return spring 60 is then effective for causing return movement of the pins, the ear portion of the pin carrier passing under the control lug until clear thereof. The control lug has its front and rear edge chamfered to prevent 40 catching of the ear 73 on these edges as it moves in its rectilinear path.

As this rearward return movement of the pin carrier occurs, the swinging plate again engages the notch 71 in the locking finger 68 and the 45 swinging plate is maintained at its normal, substantially vertical position. However, as in the preceding form, although the pin carrier is clear of the control lug it cannot move upwardly under the action of its elevating springs until the next succeeding apertures register with the pins, whereupon the fourth side of the rectilinear motion, as outlined, can occur.

Having described my invention, I claim:

1. In an autographic register, a casing including 50 a countersunk platen for supporting a plurality of superposed strips of paper, the strips of paper including apertures therein spaced longitudinally thereof, a swinging plate pivotally mounted at the base of the casing at the forward

end thereof, a vertically slidably mounted pin carrying plate on said swinging plate, the pins thereof projected upwardly therefrom and adapted to register with apertures in the strips, a lever for swinging said swinging plate and pin carrier 5 forwardly, springs urging said pin carrying plate upwardly at all times, a return spring urging said swinging plate rearwardly at all times, a stationary control lug in the casing, a portion of said vertically slidable plate movable in relation to 10 said control lug for guiding vertical movement of the pin carrying plate, said portion adapted to move across the top of the control lug in forward feeding movement of the swinging plate and under such control lug in return movement of the 15 swinging plate, and a pressure means in the casing for urging the pin carrying plate downwardly as it is swung forwardly over the control lug, whereby said portion of the pin carrying plate operates in a rectilinear path about said control 20 lug.

2. In a device of the class described, a casing provided with a platen over which a plurality of superposed strips are drawn, the strips provided with registering apertures spaced longitudinally of the strips, a carrier having depressible pins adapted to engage through the strip apertures when in registry therewith, said carrier oscillatably mounted at the forward end of the platen to initiate a feeding movement to the strips 30 when the pins are engaged with apertures in the strips, a lever for oscillating said carrier, a lock finger mounted in the casing and normally maintaining the carrier in fixed position against forward swing, said lever operating said lock finger 35 for releasing the carrier in the first phase of forward swing of the carrier, and separate means for depressing the pins operable at the completion of the forward swing of said lever.

3. In a device of the class described, a casing provided with a platen over which a plurality of superposed strips are drawn, the strips provided with registering apertures spaced longitudinally thereof, a carrier plate disposed at the forward end of the casing and having its lower end pivotally mounted, a second plate vertically slidably mounted on said first mentioned plate and including upwardly projected pins adapted to engage through the strip apertures when in registry therewith, spring means for urging the slidable plate upwardly at all times, stops limiting upward movement of the slidable plate, means for swinging said carrier plate and slidable plate forwardly for initiating a feeding movement to the strips, means for depressing the pins at the forward limit of oscillatable movement, and means for returning the plates after feeding movement.

FRITZ G. DIESBACH.
